UNITED STATES PATENT OFFICE.

HARRY WEIDA, OF HIGHLAND PARK, NEW JERSEY, ASSIGNOR TO INDIA RUBBER COMPANY, A CORPORATION OF NEW JERSEY.

MOLD AND PROCESS FOR BATTERY-JARS.

1,358,903.

Specification of Letters Patent. Patented Nov. 16, 1920.

Application filed December 18, 1919. Serial No. 345,702.

To all whom it may concern:

Be it known that I, HARRY WEIDA, a citizen of the United States, residing at Highland Park, county of Middlesex, and State of 5 New Jersey, have invented certain new and useful Improvements in Molds and Processes for Battery-Jars, of which the following is a full, clear, and exact description.

This invention relates to a mold and a 10 process for pressing or forming articles such as battery jars from plastic materials such as rubber composition.

Heretofore battery jars have been formed in a variety of ways the most common being 15 complicated and expensive devices for compressing the side walls and sometimes also the bottom. These prior devices have not only been complicated and expensive but have also been bulky, taking up a large amount of 20 space and liable to get out of order. The present invention aims to provide a new and improved type of mechanical compressor for plastic articles, such as single or plural compartment battery jars, which is simple in 25 construction, which is so small and compact that it occupies the minimum of space in the factory, which is not likely to get out of order, and which is so simple to operate and so reliable in operation that almost any un- 30 skilled workman could be employed to manufacture plastic articles therewith.

Briefly it consists of a core member which is adapted to be coated with plastic and positioned within a cellular container having 35 rigid outer and shiftable inner walls the latter in the form of separate interfitting plates that are adapted to be pressed against the plastic coating on the core member by a flexible bag or diaphragm positioned in the 40 cellular space between the rigid and shiftable walls when fluid under pressure is admitted to the bag.

A preferred embodiment of the invention is illustrated in the accompanying drawings 45 in which:

Figure 1 is a horizontal section on the line 1—1 Fig. 2 and

Fig. 2 is a vertical section on the line 2—2 Fig. 1.

50 In the drawings:

On a base 3 rest the flanges 4 of a casing 5 whose vertical faces 6 are overhung by ledges 7 which limit upward movement of side plates 8 having shouldered edges 9 55 limiting inward movement of opposed pairs

of the plates 8 as well as upward movement of a bottom plate 10 also shouldered marginally as indicated at 11. The base and casing constitute the external rigid walls and the plates 8—10 the internal shiftable walls 60 of a cellular container, a flexible impervious diaphragm or bag 12 being located in the space between the external and internal walls of the container. The bag 12 is preferably formed of vulcanized rubber in two pieces 65 marginally sealed between the base 3 and overlying flanges 4 of the casing by the clamp bolts 13. Preferably also but not necessarily the bag 12 is formed with dovetailed ribs 14 fitting into correspondingly shaped grooves 70 in the side and bottom plates 8—10 and thereby the plates are retained in approximate working relation. Through piping 15 and a valve (not shown) fluid, such as water under pressure, may be admitted to the 75 diaphragm 12 to shift the plates 8 and 10 against a plastic mass 16 previously applied to a hollow core member 17 having transverse grooves 18 for forming grid supporting cleats in the finished jars. A latch 20 80 pivoted at 21 is adapted to bridge the opening in the top of the casing to hold the core member 17 against upward vertical displacement, the opposite free end of the latch being adapted to enter a slot 22 at the opposed 85 side of the casing.

In operation plastic material, such as a rubber composition high in sulfur, is applied in a core member 17, and two or more pieces of sheet composition may be used. In illustration two pieces are first set in the grooves 18 to form the cleats, a third piece is then applied to the bottom of the core, and finally the fourth piece is wrapped around the sides of the core member flush with the bottom. 90 The coated core is then positioned within the mold and pressure of from 200 to 2000 pounds per square inch according to the character of the plastic mass is applied for from say 15 to 30 seconds to the diaphragm. 95 100 Plates 8—10 are thereby moved together as far as their interfitting shouldered edges 9—11 permit and compress the external face of the plastic mass which is to form the jar whose interior is of course formed by the core member. Excess plastic material moves upwardly into the space indicated by the numeral 23 but if desired the plates 8 may be provided with an overhang closing this space off completely and forming the upper 110 115

edge of the jar. When the diaphragm is relieved of pressure the coated core may be removed and placed in a vulcanizer. After vulcanization, which renders the plastic material hard and stiff, the jar is finished by trimming its edges even and grinding the bottom level.

In case the plates 8-10 adhere to the plastic when pressure on the diaphragm is relieved, a vacuum or partial vacuum may be applied to the diaphragm to separate them.

The simplicity of the apparatus of the present invention renders it easy to manufacture. It may also be operated more rapidly than prior constructions to produce articles of uniform shape, size and thickness of walls. The hydraulic operation of the plates through a surrounding flexible diaphragm which constrictingly presses the plates against the plastic coated core member is an especially valuable feature of the invention as it avoids the laborious and slow arrangements of the prior art.

While a hollow article is preferably formed by compressing the plates against the external faces of a plastic mass supported internally by a core, obviously it could be formed by expanding the plates through a diaphragm inclosed within the cavity formed by the plates and against the internal faces of a plastic coating lining a cavity whose walls are relatively immovable. In other words instead of forming the hollow article by moving the plates against its external surfaces, it might be formed by pressing the plates outwardly against its internal faces. But for practical reasons the illustrated form of the invention is preferred.

In its broad aspects the invention is not limited to use with a single core member inasmuch as the core could be made in a plurality of parts spaced to accommodate partitions so as to permit formation of plural compartment battery jars, the movement of opposed side plates 8 and of the bottom plate 10 transverse the opposed faces of the single core member 17 illustrated being peculiarly well suited to close the junctions of partition walls with the sides and bottom of the jar. In the formation of single compartment battery jars the bottom plate 10 may be held against movement by the diaphragm 12 if desired.

It is to be distinctly understood that the principles of the invention may be incorporated in various other forms of construction than those mentioned and therefore recourse should be had to the appended claims for an understanding of its scope.

Having thus described my invention what I claim and desire to protect by Letters Patent is:

1. A plastic shaping mold comprising a plurality of relatively movable parts, and

a single fluid pressure diaphragm for simultaneously moving some of said parts into juxtaposition with the other parts to shape a mass of plastic to a predetermined form.

2. A plastic shaping mold for making 70 hollow articles including a member having rigid side and bottom walls for shaping a surface of the article, a plurality of shiftable plates for shaping the entire opposite surface of the article, and hydraulically operable flexible means for shifting said plates to effect a shaping of the article.

3. A plastic shaping mold including a member and a plurality of plates for shaping the external and internal faces of a 80 hollow article, and flexible means for moving the plates and exerting a uniform pressure simultaneously upon all surfaces of the plastic mass in shaping it to a form predetermined by the member and plates. 85

4. A mold for hollow articles comprising plates shouldered to interfit together to form a box-like cavity, a core member adapted to be coated with plastic and introduced into said cavity, a flexible member 90 encompassing said plate members, a rigid container inclosing said flexible member, and means for conducting fluid under pressure to said flexible member whereby the plates may be forcibly shifted together to 95 compress the plastic coating on said core member.

5. A mold for making battery jars comprising a container having rigid bottom and side walls and having relatively movable 100 side and bottom plates within its rigid walls, a diaphragm intermediate said plates and container, a core member adapted to be positioned within the cavity formed by said plates, and means for conducting fluid under pressure to said diaphragm whereby a plastic mass of rubber positioned between the plates and core member may be compressed to a predetermined shape.

6. A plastic shaping mold including a 110 rigid container, a core member, shiftable plates intermediate said core member and container and shaped at their edges to mutually limit each other's movement toward the core member, a fluid-tight flexible 115 diaphragm intermediate the plates and container, and means for conducting fluid to and from the diaphragm to shift the plates relative to a plastic mass between the core and plates. 120

7. A plastic shaping mold including a core having a plurality of flat surfaces, a plurality of plates each opposed to a flat surface of the core, said core and plates being adapted to shape a hollow article externally and internally, a rigid container, flexible means within the container and operable constrictingly upon the plates to shift them to a position in predetermined spaced relation with the core whereby a plastic 125 130

coating on the core may be shaped by fluid pressure applied to the flexible means, said core and plates being open upwardly to permit the escape of an excess of material.

5 8. A plastic shaping mold including a member and a plurality of plates for shaping the external and internal faces of a hollow article, flexible means confining said plates loosely in working relation and 10 adapted under pressure to shift the plates and thereby shape a plastic mass to a given form.

9. A plastic shaping mold including a former adapted to be coated with plastic, 15 and a container adapted to receive the coated former and including outer rigid walls and a plurality of separate and independent inner walls, and means intermediate the walls of the container for shifting some of said inner walls to compress the 20 plastic coating on the former.

10. A plastic shaping mold including a former adapted to be coated with plastic, and a container adapted to receive the coated former and including outer rigid 25 walls and a plurality of separate and independent inner walls, and a fluid operable diaphragm intermediate the walls for shifting one or more of said inner walls to compress the plastic coating on said former. 30

11. The method of manufacturing hollow rubber articles consisting in shaping a plastic mass roughly to form by hand, finally to form by mechanical pressure, and finally fixing the shape of the plastic mass by vul- 35 canization with one of its surfaces entirely free and unconfined.

Signed at New Brunswick, county of Middlesex, and State of New Jersey, this 10th day of December, 1919.

HARRY WEIDA.
